(57) CLAIM

The ornamental design for an article of furniture, as shown and described.

DESCRIPTION

FIG. 1 is a front perspective view of an article of furniture showing our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines illustrate portions of the article of furniture that form no part of the claimed design. The article of furniture may be a table or a seat such as a chair or a barstool.

1 Claim, 7 Drawing Sheets
